UNITED STATES PATENT OFFICE.

THOMAS F. O'NEILL, OF NEW HAVEN, CONNECTICUT, AND RAYMOND J. MILLER, OF NEW YORK, N. Y., ASSIGNEES TO ALPHONSE F. PIEPER, OF NEW YORK, N. Y.

WARM-AIR SYRINGE.

Original No. 1,542,472, dated June 16, 1925, Serial No. 752,103, filed November 25, 1924. Application for reissue filed April 1, 1927. Serial No. 180,104.

Fig. 1 is a side view of a warm-air syringe constructed in accordance with our invention.

Fig. 2 is a sectional view showing the same set into an electric heater.

This invention relates to improvement in warm-air syringes, such as are commonly used in dentistry and surgery. Most dentist's equipment includes an electric heater, 10 into which tubular liquid containers may be placed and by which the liquid may be heated to the desired temperature. Air for drying cavities, etc., is commonly used, and the object of this invention is to provide a 15 device by which air may be readily heated in an ordinary electric heater, without requiring further equipment than that commonly possessed by dentists and surgeons, and the invention consists in the construction as hereinafter described and particularly recited in the claims.

In carrying out our invention, we employ a tubular casing 5 of copper or any other suitable material, provided with a head 6, 23 preferably having threaded engagement with the casing, so that it may be removed. This head mounts an inlet-nipple 7 and an outlet-nipple 8, and is preferably provided with a centrally-arranged vent 9, the inlet-nipple 30 being connected with the usual source of air-supply either from a compressed-air tank or from a foot or otherwise operated bellows, while the outlet-nipple 8 is provided with a small perforation 10 through which 35 air may escape. The inlet-nipple 7 is connected with one end of a coil 11 within the casing 5. From the lower end of the coil the pipe is extended upward through the coil and into connection with the outlet-nipple 8.

The casing may be filled, or partly filled, 45 with liquid, if desired, as this will facilitate the distribution of heat. The casing corresponds in size to standard spray bottles and is adapted to be entered into a standard electric heater 12, so that air in the coil is heated to the desired temperature, and a sufficient amount of air will be uniformly heated to last for the desired period.

A feature of this invention is that it can be produced at a comparatively low cost and can be heated in various forms of heaters now commonly on the market and in the equipment of dentists and surgeons, thus avoiding the expense of a special electrical 55 device for heating air.

Another advantage of this invention is that the device will maintain an even temperature of air while in use, as the heated air in the coil must escape before any cold air 60 can enter, and the air is evenly heated, which is not possible when it is heated by passing over electrically-heated coils.

We claim:

1. A warm-air syringe, comprising a tubular casing adapted to be entered into an electric heater, said casing provided with a removable head, said head provided with inlet- and outlet-nipples, a coil within said casing, one end of the coil connected with the inlet-nipple, and the other end of the coil connected with the outlet-nipple. 65

2. A warm-air syringe, comprising a tubular casing adapted to be entered into an electric heater, said casing provided with a removable head, said head provided with inlet- and outlet-nipples, a coil within said casing, one end of the coil connected with the inlet-nipple and the other end of the coil connected with the outlet-nipple, and a vent 75 through said head.

3. In combination, an electric heater in the form of a receptacle, a coiled tube removably inserted in said receptacle, one end of said tube being connected to an air supply, 85 and an outlet nipple connected to the other end of said tube.

4. In combination, an electric heater in the form of a receptacle, a casing removably inserted in said receptacle, a coiled tube hung 90 in said casing, and inlet and outlet nipples mounted on the top of said casing and connected respectively to the ends of said tube.

5. In combination, an electric heater in the form of a receptacle, a casing inserted 95 in and supported by said receptacle, a coiled tube in said casing, means at one end of said tube for connection with an air supply, a

syringe nozzle at the other end of said tube, said casing, tube, connection and nozzle being rigidly secured together and removable from said heater as a unit.

5. 6. In combination, an electric heater in the form of a well with a heating element in the wall thereof, a coiled tube with terminals at the same end of the coil removably

inserted in said well, a hose connecting nipple on one of said terminals, and an outlet ¹⁰ nipple on the other of said terminals.

In witness whereof, we have hereunto set our hands at New York, New York, this 21st day of February, 1927.

THOMAS F. O'NEILL.
RAYMOND J. MILLER.
